UNITED STATES PATENT OFFICE.

REXFORD O. ANDERSON, OF HOUSTON, TEXAS.

HEATING APPARATUS.

Application filed November 5, 1920. Serial No. 422,079.

To all whom it may concern:

Be it known that I, REXFORD O. ANDERSON, a citizen of the United States, residing at Houston, in the county of Harris and 5 State of Texas, have invented certain new and useful Improvements in a Heating Apparatus, of which the following is a specification.

This invention relates to new and useful 10 improvements in a heating apparatus.

One object of the invention is to provide an apparatus by means of which heat may be readily conveyed from one fluid to another without bringing the two fluids into 15 direct contact.

With the above and other objects in view, the invention has particular relation to certain novel features of construction, operation and arrangement of parts, an example 20 of which is given in this specification and illustrated in the accompanying drawings, wherein:—

Figure 1 shows a side view of the device, partially in section, and

25 Figure 2 shows an end view, shown partially in section, and with the head removed.

Referring now more particularly to the drawings, the numeral 5 designates an enclosing shell and on opposite sides thereof are the fluid receptacles 1 and 6, which are incorporated with the shell. The receptacles 1 and 6 are connected by means of the tubular coils 4 arranged side by side, and 30 united to the receptacles by the unions 2. These coils are made of metal having good heat conducting properties and suitable to the fluids to be used. In formation, the coils are coiled from the center into the 35 shape of a conical spiral, as shown in the figures. These coils are reversely spiralled from the center of the tubes of which they are formed, the two ends of the tube lying parallel and alongside approximately 40 throughout their entire length so that the inlet and outlet ends will lie side by side and the mean temperature between the two ends of the coil will be the same throughout their length thus affording an even temperature 45 throughout the cross section of the coil. The respective receptacles 1 and 6 have the inlet and outlet openings 7 and 8, respectively, and cold fluid may be admitted through the inlet 7 into the receptacle 6

and it will pass thence through the coils 4 55 and into the receptacle 1 and out through the opening 8, thus cooling the coils.

The shell 5 has an inlet opening 10 through which the other fluid is introduced into the interior of the shell, usually in the 60 form of vapor and under pressure, and the entering fluid is spread by the conical baffle plate 3 and distributed out through the shell and passes over and between the coils and it is suddenly chilled by them. Baffle 65 plates 11 are provided, which force the fluid to take a devious route through the coils not allowing it to pass directly in the interior without coming in close contact with the coils. As it passes through the 70 coils 4, the fluid condenses and collects in the bottom chambers 9 and passes out through the openings 9', as shown, or at other points suitably located.

It is to be here noted that the baffles 3 and 75 11 are held in place by means of U-bolts which connect them to the turns of the coil. However, other suitable fastening means may be employed if desired.

The apparatus herein described is particularly adapted for use in distilling oils, for 80 extracting gasoline from gas and for other similar purposes.

What I claim is:—

1. A device of the character described, including a shell, having an inlet and outlet opening, a fluid conducting tube within the shell formed into a conical shaped spiral, a pair of receptacles incorporated in the shell, the respective ends of said coil entering said 85 receptacles, an inlet entering one receptacle, an outlet entering the other receptacle, said coils being provided for the circulation of hot fluid therethrough to heat the fluid within the shell, and fluid collecting 90 chambers formed within said shell.

2. A device of the character described, including a shell adapted to contain a fluid and provided with an inlet and a series of outlets, a series of coils within the shell, 100 formed into a conical shaped spiral, a pair of receptacles incorporated into said shell, the respective ends of said conduit entering the corresponding receptacles, an inlet entering one of said receptacles, an outlet 105 leading from the other receptacle, providing for the circulation of a heating fluid through said coils, fixed collective chambers formed

within the shell and each chamber having an inlet and an outlet.

3. A device of the character described including a shell, a fluid conducting tube reversely coiled from its center into a general conical contour and enclosed within the shell, the respective ends of the coil lying parallel and adjacent throughout their entire length and fluid receptacles formed

within the shell which the respective ends 10 of said coil enter.

In testimony whereof I have signed my name to this specification in the presence of two subscribing witnesses.

REXFORD O. ANDERSON.
